UNITED STATES PATENT OFFICE.

GEORGE W. BLACKBURN AND WILLIAM F. CORDRAY, OF COLUMBUS, OHIO;
SAID CORDRAY ASSIGNOR TO HARRIET CORDRAY, OF SAME PLACE.

FURNACE-GRADE.

SPECIFICATION forming part of Letters Patent No. 325,651, dated September 8, 1885.

Application filed March 22, 1884. (No model.)

To all whom it may concern:

Be it known that we, GEORGE W. BLACKBURN and WILLIAM F. CORDRAY, citizens of the United States, residing at Columbus, in the county of Franklin and State of Ohio, have invented certain new and useful Improvements in Furnace-Grates, of which the following is a specification, reference being had therein to the accompanying drawings, in which—

10 Figure 1 is a plan or top view of the grate. Fig. 2 is a longitudinal vertical section of the same. Fig. 3 is a perspective view of the front tumble-bar. Fig. 4 is a side view of one of the tipping grate-bars.

15 Our invention relates to improvements in furnace grate-bars; and the objects of our improvements are to provide a furnace having a series of stationary grate-bars, made narrower at the fore end and curved upward at the rear end, with one or more grate-bars provided with a bearing in the middle of their length, and adapted to have their fore end tipped downward and again locked on the same level as the others. We attain these objects by the 25 construction illustrated in the accompanying drawings, in which—

A represents the side walls, and A' the bridge-wall, of a furnace provided with the improved grate-bars B. Each of these bars is so formed 30 that the upper face of its forward portion, b, (extending about one-half of the length of the grate-bar,) is narrower than the upper face, b', of the rear portion, so that the air-openings c in the front end of the furnace are wider than 35 the air-openings c' in the rear end. The draft is thus improved at the front of the furnace, where it is most needed, time is saved in getting up steam, and the danger of overheating or blistering the boiler over the bridge-wall is 40 obviated.

To protect the bridge-wall A against intense heat, and thus permit ordinary bricks to be used in its construction, the rear portion, b', of each grate-bar is gradually curved upward, 45 and extends on a level with the top of the bridge-wall. The curve given to said rear portion, b', is substantially a segment of a circle, and permits a poker to follow the curve, turn any clinkers upside down, and bring 50 them forward to be easily removed. The grate-bars are supported at the rear end upon the

transverse bars D and at the front upon the transverse bars D'.

To facilitate the removal of cinders, clinkers, &c., the two grate-bars B' next to the last 55 grate bar on each side of the furnace are constructed so as to have their forward end easily tipped downward. For this purpose they are provided, about the middle of their length, with a semi-cylindrical bearing, b', in the under side thereof, to rest upon trunnions b', projecting from the side of the two adjoining grate-bars. (A transverse bar extending across the ash-pit may be used in place of the trunnions.)

The two tipping grate-bars B' are connected 60 at their fore end by a tumble-bar, E, the ends of which enter mortises or recesses b' in the sides of the bars B'.

To retain the front end of the bars B' on a level with the bars B, there is projecting from 70 the front of the tumble-bar E a lug, e, to rest upon a spring-latch, f, passing through the front wall of the furnace. This latch is carried by a spring, F, secured to the front wall at f', and is provided with a handle, f', at its 75 upper end. The ends of both the latch f and the lug e of the tumble-bar are beveled, so as to readily pass each other when the grate-bars B' are to be returned to their normal position.

The grate-bars B and also B' are provided 80 with the usual check-pieces or side projections, b', at the ends and intermediate portions thereof, to prevent their warping and retain them at proper distances apart.

The rear half of the tipping grate-bars is 85 slightly heavier than the front portion; but when coal and clinkers are piled upon said forward portion it will have a tendency to tip down, and said motion is arrested by a chain, C, having one end secured to the rear portion 90 of the grate-bar, and the other to the rear wall or to some other stationary part. When the bars have been relieved by the fireman of the coal and clinkers upon their front end, they will return to their normal horizontal position 95 either automatically or with the help of the fireman.

Having now fully described our invention, we claim—

1. The combination of stationary grate-bars, 100 having their rear portion curved upward and provided with trunnions or their described

equivalents, with the grate-bars B', connecting-bar E, having lug e, and the latch f, substantially as and for the purpose described.

2. The combination of stationary grate-bars, having their rear portion curved upward in substantially the form of a segment of a circle, with similarly-curved bars adapted to have their forward end tipped downward, and a connecting-bar having its ends entering recesses

in the pivoted grate-bars, substantially as and for the purpose described.

In testimony whereof we affix our signatures in presence of two witnesses.

GEORGE W. BLACKBURN.
WM. F. CORDRAY.
